UNITED STATES PATENT OFFICE.

SÁMUEL PAPP, OF LOWELLVILLE, OHIO.

RAIL-JOINT FASTENER.

1,425,683.

Specification of Letters Patent. Patented Aug. 15, 1922.

Application filed April 1, 1922. Serial No. 548,568.

To all whom it may concern:

Be it known that I, SÁMUEL PAPP, a citizen of the United States, residing at Lowellville, in the county of Mahoning and State 5 of Ohio, have invented certain new and useful Improvements in Rail-Joint Fasteners, of which the following is a specification.

This invention relates to rail joints, having for an object to provide a novel and improved rail joining means which eliminates the use of bolts, which latter as is well known suffer from the disadvantage of loosening under the vibration due to continued travel of trains on the tracks.

For further comprehension of the invention, and of the objects and advantages thereof, reference will be had to the following description and accompanying drawings, and to the appended claims in which 20 the various novel features of the invention are more particularly set forth.

Fig. 1 of the drawings is a perspective view showing my improved rail joint as applied to a pair of rail ends.

Fig. 2 is a detail perspective view of one of the joint elements.

Fig. 3 is a horizontal sectional view showing a modified form of the invention, this view being taken on the line 3—3 of Fig. 4.

Fig. 4 is a transverse vertical sectional view taken on the line 4—4 of Fig. 3.

In the drawings the reference numeral 10 indicates a pair of rail ends to which my device is applied. This device comprises a 35 pair of members which engage each side of the rails and which are in the main of similar shape. These members comprise the flat base elements 11 and 12 respectively, which engage under the rail and from the 40 outer edges of which inclined members 13 and 14 extend inwardly over the base flanges of the rail in contact therewith. From the inner edges of these members integral fish-plate elements 15 and 16 project upwardly 45 in contact with the web of the rail.

These two members, as just described, which form the respective halves of a chair for the rail, are locked together by engagement of the inner edge portions of the base 50 elements 11 and 12 with one another. To this end the element 11 is formed with a hooked lateral projection 17 engaging under a complementary projection 18 on the base element 12.

The device is adapted to be secured to the tie, indicated at 20, by means of spikes 21 whose heads engage over the inclined parts 13, 14. To cause said spikes to hold the two members against longitudinal displacement, vertical grooves or notches 22 are formed in 60 the sides of the members in which the spikes are engaged.

When the device is applied to a new track, just being laid, the two members can be positioned together and the rail ends inserted therebetween. When a single rail is to be removed one of the members must be moved longitudinally until its hooked part is freed from the hooked part of the other member.

In the modification shown in Figs. 3 and 4 I provide a pair of members similar to the members shown in Fig. 1 and comprising the corresponding elements 11', 12', 13', 14', 15' and 16'. In this construction the vertical element 15' is formed near opposite ends with hooks 25, 26 which project through slots 24 in the webs of the rail ends and which are vertically spaced. The other vertical element 16' is formed with a pair of recesses 27, 28 which enter longitudinally from one end and receive the said hooks, the parts being so arranged that the upper hook 26 is received in the longer recess 28 so as not to weaken the member. In applying this modified form of the device the member carrying the hooks is first engaged with the rail, and the other member is then inserted longitudinally into position until the hooks engage in the proper elements 80 formed in the inner ends of the recesses, after which the device is spiked to the tie.

Having thus described my invention what I claim as new and desire to protect by Letters Patent of the United States is as follows:

A rail joint comprising a pair of members engaging opposite sides of the rail and having base elements extending under the rail and interlocked together, and hooked elements on one member projecting through slots in the rail and engaging in retaining recesses in the other member said recesses communicating with one end of said last member.

In testimony whereof I have affixed my 105 signature.

SÁMUEL PAPP.
